UNITED STATES PATENT OFFICE.

HERMANN LEHMANN AND FRITZ HOHNBERG, OF MAGDEBURG, GERMANY.

RECOIL-REDUCING MEANS FOR GUNS.

1,227,161.

Specification of Letters Patent.

Patented May 22, 1917.

Application filed April 14, 1914. Serial No. 831,802.

To all whom it may concern:

Be it known that we, HERMANN LEHMANN and FRITZ HOHNBERG, subjects of the King of Prussia, residing at Magdeburg, 5 German Empire, have invented certain new and useful Improvements in Recoil-Reducing Means for Guns, of which the following is a specification.

The invention relates to recoiling guns 10 and its object is to provide guns of this kind with a device, through which the recoil of the gun is considerably reduced while the stability of the gun carriage is sufficiently maintained.

15 This object is attained in accordance with the present invention, by utilizing a mass set in motion through the recoil of the gun for the annihilation of the recoil energy.

In the accompanying drawings, several 20 embodiments of the invention have been illustrated.

Figure 1 is a side view of one embodiment of the invention showing a gun and the appurtenant parts;

25 Fig. 2, a front view of the muzzle;

Fig. 3, a section along line I—I of Fig. 1;

Fig. 4, a section along line II—II of Fig. 1;

Fig. 5, an axial section of Fig. 1;

30 Fig. 6, a transverse section along line III—III of Fig. 5;

Fig. 7, a top plan view of Fig. 1;

Fig. 8, a longitudinal section similar to Fig. 5 of a second embodiment of the invention;

Fig. 9, a transverse section along line IV—IV of Fig. 8 seen from the left;

35 Figs. 10 and 11 show elevation and plan views respectively and in larger scale of switch 13, being a detail of Fig. 8;

Figs. 12 and 13, front and side views also in larger scale, of the latch bolt 12, being a detail of Fig. 8;

Fig. 14 shows a longitudinal section similar to Fig. 5 of a third embodiment of the invention;

Fig. 15, a similar view to Fig. 14 of a fourth embodiment and

Fig. 16 the corresponding breech end 50 view.

The embodiment illustrated in Figs. 1 to 7 will now first be described.

The gun 1 is guided on the cradle 2. A 55 checking weight 3, see Figs. 1, 5 and 7, is mounted to slide axially upon the breech

end of the gun. Several small hydraulic brake cylinders 1^a are provided on the gun, their pistons 4 each being pushed rearwardly by a spring 5. Fluid passages (not shown on the drawing) are provided in the pistons 4 or in the cylinders 1^a, for the purpose of making inelastic, the blow of the checking weight 3 against the pistons. 60

On the muzzle of the gun 1, a screen 6 is provided and rigidly connected with the checking weight 3, by means of connecting rods 7. The rods 7 are carried in guides 1^b near the muzzle of the gun. Two helical springs 8 and 9 are provided in the cradle 2, see Figs. 5 and 6, which, however, may be substituted by other accumulators. The helical spring 9 constitutes the main counter-recoil spring. It abuts with its forward end against a lug 1^c of the gun, see Fig. 5, and with its rear end against an abutment 2^b 70 which is rigidly connected with the cradle 2, thus holding the gun in its forward position. The helical spring 8 of the checking weight 3 abuts with its forward end against the forward end wall 2^a of the cradle 2, and with its rear end against a lug 3^a of the checking weight 3, thus tending to hold the checking weight in the position in which it abuts against the collar 1^c of the gun. 75

Apart from the springs 8 and 9, a hydraulic brake may be provided, which in known manner operates as recoil and counter-recoil brake. In contradistinction to the formerly known recoil brakes which consume the greater portion of the recoil energy, the here 80 mentioned recoil brake would, in the present case, act to annihilate a comparatively small portion of the recoil energy, as the greater portion thereof will now be annihilated by the impact of the weight 3 against 85 the pistons 4.

During the firing, the gun runs to the rear. At the moment when the projectile leaves the muzzle, the recoil amounts, however, only to a few centimeters. The projectile then speeds on through the boring of the screen 6 without being guided, and the powder gases act on the screen so that the screen 6, the connecting rods 7 and the checking weight 3 are moved forward, with 100 only a slight resistance from the spring 8. The weight 3 then strikes against the pistons 4. The forward acting energy of the checking weight 3 will then be annihilated in the cylinders 1^a which are filled with 105 110

glycerin, whereby a comparatively great part of the recoil energy is likewise annihilated. The remaining and not annihilated part of the recoil energy tends after 5 the counter-shock to run the gun rearward, the latter bringing with it the checking weight 3.

During the recoil, the counter-recoil spring 9 will be compressed. The remaining recoil energy that had not been consumed by the impact, will now be entirely annihilated with the assistance of the above-named recoil brake. Thereupon the gun 10 will be driven forward through the spring 15 9, while the checking weight 3, actuated by the spring 8 is returned to its initial position. The gun is then again ready for firing.

In the embodiment illustrated in Figs. 20 8 to 13, the screen arranged on the gun muzzle is dispensed with. The gun counter-recoil spring 9 is here arranged as already described. The spring 10 for the checking weight 3 rests with its rear end against the 25 lug 2^c situated on the cradle 2, and with its forward end against the collar 11^a on the rod 11. This rod is secured to a lug 3^b on the checking weight 3 and may contact with a spring actuated latch bolt 12, which 30 is seated in a recess 2^e in the cradle 2. At its upper end, the latch bolt 12 is provided with a cut 12^a, see Figs. 12 and 13, in which the dog 13 engages, see Figs. 8 to 11, this dog being revolubly mounted in a seat 1^b 35 in the gun 1 and pressed downwardly by a spring.

Before firing, the spring 10 of the checking weight 3 is compressed to a comparatively great amount. As soon as the firing 40 takes place, the gun recoils. Then the dog 13 immediately engages in the cut 12^a of the latch bolt 12, drawing the latter upward, so that the collar 11^b on the rod 11 is set free, and the spring 10 released. 45 As a consequence, the checking weight 3 is driven forward and ultimately impacts with the pistons 4, so that the energy of the forward movement is completely consumed and the recoil energy of the gun substantially 50 annihilated. During the continued recoil, the gun brings with it the weight 3 and the rod 11, so that not only the spring 9, but also spring 10 is compressed. When the recoil is finished, the gun, together with 55 the checking weight 3, runs forward, actuated by springs 9 and 10. The checking weight will, however, come to rest as soon as the collar 11^b of the rod 11 engages with the latch bolt 12, which, at the time, has been drawn back into its position of rest by its spring. The gun thereupon continues 60 its forward movement alone. Toward the end of this forward movement of the gun, the spring actuated dog 13, slides away over 65 the head of the latch bolt 12, but returns

again into the position shown in Fig. 8 at the end of the forward movement of the gun.

The embodiment illustrated in Fig. 14 differs from that illustrated in Figs. 8 to 13, only therein that a screen 6 is arranged in front of the muzzle of the gun 1, and in the previously described manner is connected with the checking weight 3. Through this arrangement the forward movement of the checking weight 3 will be accelerated 75 not only by means of the spring 10, but also by the action of the powder gases ejected from the gun against the screen 6.

As a consequence, the checking weight 80 impacts with the pistons 4 with greater velocity and earlier than is the case in the above described embodiment, so that the recoil of the gun is limited to a minimum.

The arrangement illustrated in Figs. 15 85 and 16, differs from that shown in Fig. 14, only therein that the pistons 4, with their brake cylinders, have been substituted by a collar 1ⁱ rigidly secured to the gun, and that a coupling has been provided by means 90 of which the checking weight may be connected with the gun. This coupling consists in this embodiment of a pawl 14 seated on the checking weight 3, which pawl is revoluble on the journal 15, and is actuated 95 by a spring 16. The pawl 14, which in Fig. 15 has been shown out of place, carries a bent ledge 14^b with which a finger 17 attached to the cradle 2 co-operates.

The shock or impact of the checking 100 weight 3 against the gun 1, or the collar 1ⁱ is therefore elastic. As soon as the impact takes place, the pawl 14, set free from the finger 17, grips over the collar 1ⁱ, actuated by the spring 16, so that the weight 3 does 105 not, directly after the impact, rebound from the collar 1ⁱ, but being coupled to the gun, recoils together with the same. Directly after the checking weight has attained the same recoil speed as the gun, or shortly after 110 this condition has commenced, the pawl 14, through the co-operation of the ledge 14^b and the finger 17, is brought out of engagement with the collar 1ⁱ of the gun. The gun thereupon runs rearwardly, together with 115 the checking weight until the recoil energy has been completely consumed.

If the pawl 14 is left out, the checking weight 3 will then repeatedly hammer on the collars 1^g and 1ⁱ, and even in this case 120 will contribute to the annihilation of the recoil energy.

We claim:—

1. A recoil checking device for guns having a cradle wherein the gun is mounted to 125 slide, a weight mounted to slide on the gun and means for driving said weight in the opposite direction to the gun during the recoil in order to impact against the gun after the gun has traveled a portion of its recoil 130

length, thus obstructing the remainder of the recoil movement of the gun.

2. A recoil checking device for guns having a cradle wherein the gun is mounted to slide, a weight mounted to slide on the gun and means for driving said weight in the opposite direction to the gun during the recoil, an abutment on the gun against which said weight strikes after the gun has traveled a portion of the recoil length, thus partly checking the recoil, said means comprising a screen positioned in front of the muzzle of the gun, said screen having rigid connections with said weight and constructed to obstruct the free passage of the escaping powder gases.

3. A recoil checking device for guns having a cradle wherein the gun is mounted to slide, a weight mounted to slide on the gun and means for driving said weight in the opposite direction to the gun during the recoil, an abutment on the gun against which said weight strikes after the gun has traveled a portion of the recoil length, thus partly checking the recoil, said means comprising a screen positioned in front of the muzzle of the gun, said screen having rigid connections with said weight and constructed to obstruct the free passage of the escaping powder gases, said abutment being provided with shock absorbing buffers.

4. A recoil checking device for guns having a cradle wherein the gun is mounted to slide, a weight mounted to slide on the gun and means for driving said weight in the opposite direction to the gun during the recoil, an abutment on the gun against which said weight strikes after the gun has traveled a portion of the recoil length, thus partly

5. A recoil checking device for guns having a cradle wherein the gun is mounted to slide, a weight mounted to slide on the gun and means for driving said weight in the opposite direction to the gun during the recoil, an abutment on the gun against which said weight strikes after the gun has traveled a portion of the recoil length, thus partly checking the recoil, said means comprising a screen positioned in front of the muzzle of the gun, said screen having rigid connections with said weight and constructed to obstruct the free passage of the escaping powder gases, a spring acting between said weight and said cradle to resist the forward movement of said weight and return it to its initial position at the end of the counter recoil of the gun.

In testimony whereof the foregoing specification is signed in the presence of two witnesses. 70
